US00D660714S

(12) **United States Design Patent**
Castillo Higareda et al.

(10) **Patent No.:** **US D660,714 S**
(45) **Date of Patent:** **** May 29, 2012**

(54) **BOTTLE**

(75) Inventors: **Jose de Jesus Castillo Higareda**, Racine, WI (US); **Peter M. Neumann**, Racine, WI (US); **Holger Hampf**, Ventura, CA (US); **Matthew D. Hern**, Malibu, CA (US); **Gary B. Swetish**, Racine, WI (US); **Benjamin R. Lloyd**, Milwaukee, WI (US)

(73) Assignee: **S.C. Johnson & Son, Inc.**, Racine, WI (US)

(**) Term: **14 Years**

(21) Appl. No.: **29/380,459**

(22) Filed: **Dec. 6, 2010**

(51) LOC (9) Cl. **09-01**

(52) U.S. Cl. **D9/543**; D9/565; D9/575

(58) Field of Classification Search **D9/685**, D9/516, 523, 530, 541–543, 563, 569, 571, D9/575; 215/379, 381–382, 384; 222/382

See application file for complete search history.

Primary Examiner — Carol P Rademaker

(57) **CLAIM**

The ornamental design for a bottle, as shown and described.

DESCRIPTION

FIG. 1 is a top, front, and left side perspective view showing our new bottle;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines appearing in FIGS. 1–7 define the bounds of the claimed design and/or disclose environment related to the claimed design, and therefore form no part of the claimed design.

1 Claim, 7 Drawing Sheets
